UNITED STATES PATENT OFFICE

NELS P. PETERSEN, OF LOS ANGELES, CALIFORNIA, ASSIGNOR TO ANTONETTE M. E. PETERSEN, OF LOS ANGELES, CALIFORNIA

FRUIT VENDING MACHINE

Application filed August 31, 1927. Serial No. 216,567.

My invention is a fruit vending machine particularly adapted for vending such fruits as oranges, apples, or fruits having similar characteristics.

5 An object of my invention in a fruit vending machine is to have the fruit arranged in a stack or in a column and to vend the lowermost article in the column, at the same time interposing a barrier underneath 55 the fruit or other article next above, this barrier supporting the stack. In connection with this object my invention comprises the mechanism for releasing a trap or trap door on which the stack of fruit is normally supported, and before this is released, inserting 60 the barrier, the barrier being provided with a resilient lost motion connection which, in the insertion, prevents damage to the fruit.

Another detailed object of my invention 20 is in connection with the closing of the trap door by the return motion of the arm operating the vending mechanism and withdrawing the barrier, which also may have a delayed motion, assuring the door being closed 25 before the barrier is withdrawn, and dropping the stack of fruit onto the trap door.

A further detailed object of my invention 30 is in mounting a pinion on a fixed axis and having upper and lower racks engaging therewith, the lower rack being directly connected to a hand operated rod for working the vending machine. The lower rack, moreover, has a trigger for releasing a catch which holds the trap door of the magazine 35 closed, and also this lower rack has an arm with a roller thereon which closes the trap door after the vending operation. The upper rack has a barrier operatively connected therewith and movable to be inserted 40 in the magazine, this barrier being constructed with a partly slideable or delayed motion connection with the upper rack.

Another object of my invention in connection with the coin control feature of my 45 vending mechanism is in the employment of a pivotally mounted latch which has a device for engaging a coin on edge and on the forward movement of the lower rack, when the coin is inserted, the latch is depressed, allowing the working of the vend-

ing machine. However, if there is no coin inserted, a stop device is brought into action and prevents movement of the lower rack.

Other detailed objects and features of my invention such as the particular arrangement and mounting of the pinion, the rack bars, the arms for controlling the magazine and the particular construction of the barrier, its lost motion connection, etc., will be detailed in the following description: 55

My invention as applied to a fruit vending machine having a single stack of fruit is illustrated in the accompanying drawings, in which:

Figure 1 is a vertical longitudinal section 65 through my machine taken on the line 1—1 of Fig. 3, this view showing the position of the mechanism before the vending operation.

Figure 2 is a section similar to Fig. 1 70 showing the position of the mechanism after vending an article such as an orange.

Figure 3 is an irregular vertical transverse section on the line 3—3 of Fig. 1 in 75 the direction of the arrows.

Figure 4 is a partial horizontal section on the line 4—4 of Fig. 1 in the direction of the arrows.

Figure 5 is a partial elevation of the lower 80 rack bar taken in the direction of the arrow 1 with a side or cover plate removed showing the non-return control for the rack bar.

Figure 6 is a vertical longitudinal section 85 on the line 6—6 of Fig. 3 in the direction of the arrows showing part of the barrier and the lost motion connection with the upper rack bar.

Figure 7 is a view similar to Fig. 6 with the barrier inserted in the magazine.

The general vending mechanism is 90 mounted in a suitable base housing 11 having an upper casing 12 and in this latter is mounted a magazine 13 for holding the fruit or articles to be vended. This magazine is shown as tubular and is open at the 95 bottom 14, which bottom is closed by a trap door 15 pivotally connected to one side of the magazine, as indicated at 16. The trap door has a cam section 17 on the bottom and is provided with a block 18 at its free end. 100

This block is engaged by a catch 19 having a tooth 20 engaging in a notch 21 of a trap door. This catch is pivotally mounted as indicated at 22 on the side of the magazine, 5 the upper end 23 of the catch being normally pressed outwardly by a spring 24 which is secured to the lower part of the magazine. On one side of the magazine there is a horizontal slot 25 for insertion of 10 the barrier, as hereunder set forth (note Figs. 1 and 2).

The coin control features connected to my vending machine comprise a coin chute 30 indicated in phantom in Fig. 1, this leading 15 the coin to a position indicated at 31, in which position the coin engages a projecting nub 32 which has an inclined upper edge 33, this nub being mounted on a latch 34 which is pivoted on a pivot pin 35 secured to a block 36 extending upwardly from the base 37 of the vending machine. This latch is normally pressed upwardly by 20 a spring 38 fitting in a socket 39 and coiled around a stem 40. A stop post 41 is also 25 secured to the latch slightly to one side of the nub 32 which is in alignment with the edge of the coin and the stop post 41, being on one side of the coin. The upward movement of the latch is limited by pins 30 42 secured to the upper part of the block 36 (note Figs. 1 and 2).

The nub, the stop post and the latch cooperate with the slidable rack structure of the vending mechanism constructed as follows: An operating arm or rod 45 has a handle 46 and is slidable through an aperture 47 in the front of the housing 11. This is connected to a rack bar 48 which is slid- 35 able in a suitably mounted guide-way 49 in the vending machine. On one side of this rack bar there is secured a plate 50. This plate has a rounded forward edge 51 to engage the edge of the coin and also has a stop pin projected from one side. When the 40 handle 46 is pulled outwardly, if there is no coin in the position indicated at 31, the stop pin 52 engages the upper part of the stop post 41, and is thereby prevented from outward movement, thus blocking the operation 45 of the vending machine.

However, when there is a coin in a position of 31, this is shoved in a forward direction by engaging the curved surface 51 of the plate 50. The action presses on the nub 55 32 thereby pivoting the latch lever 34 downwardly to such an extent that the stop pin 52 passes over the top of the stop post 41. The latch lever then returns to its normal position under the action of the spring 38. 60 The relative position of the above elements are illustrated in Figs 1 and 2.

On return movement, on thrusting in on the handle 46, the stop pin engages the upper curved surface 53 of the stop post 41, there- 65 by depressing the latch lever 34 and allow-

ing return of the parts to their original positions. In order to prevent a return motion of the rack bar when once started, I provide a series of notches 55 on the bottom of this bar, with a pair of recesses 56 at the end of the notches. A dog 57 is mounted on a pivot pin 58 in a pocket 59 of the block 36. The lower end 60 of this dog is attached by a spring 61 to the block, this allowing the toothed end 62 to engage in the notches 55 and prevent a return movement of the rack bar when it is once started in its movement, until the movement in either direction is completed (note Fig. 5).

The closing and opening mechanism for the magazine is constructed as follows: An arm 63 is connected by means of a stud 66 to the rack bar 48 and at its upper end it carries a roller 67. At the end of the rack bar there is a trigger arm 68 which has a forwardly turned flange 69, the action being as follows: When the handle 46 is drawn outwardly, thus pulling the rack, the flange 69 of the trigger 68 engages the upper end of the catch 23, this action compressing the spring 24 and pulling the tooth 20 out of engagement with the notch 21 of the trap door 15, so that this door is free to drop, due to the action of gravity and also the weight of the fruit or other articles to be vended resting on this trap door. This action is represented in Fig. 2.

On the return movement of the rack bar 48, the roller 67 engages the cam section 17 of the trap door 15 and forces this into its closed position. After it is closed, the trigger moving away from the catch 19 allows the spring 24 to return the catch to its normal position with the tooth 20 in engagement with the notch 21 of the trap door, 100 thus holding it in locked position as shown in Fig. 1.

The transfer of motion is effected by the rack bar having teeth 75 on its upper edge which mesh with a pinion 76 which is mounted on a stud 77 on a frame 78 contained in the housing 11 (Fig. 3). The rotation of the pinion actuates an upper rack bar 79 having teeth 80, this rack bar sliding in an upper guideway 81 contained in the housing 11. A tension spring 82 caught between a screw 83 on the upper rack bar and a hook 84 on the front of the housing 11 normally hold the two rack bars and the pinions and other associated parts in the 110 position shown in Fig. 1. After pulling out on the handle 46 the spring is tensioned, as shown in Fig. 2, and returns these parts to their normal inactive position.

A barrier 90 is formed of a plate 91 having a forked inner end 92, the forked end diverging as shown in Fig. 4. This barrier plate is slidable in a guideway 93 in the upper part 94 of the general frame 78 (Fig. 3). A block 95 is firmly secured to the 120

under surface of the barrier plate and has a horizontal opening 96 therethrough, in which slides a rod 97 having a cotter pin 98 at its outward end. This rod is rigidly connected to a second block 99 and there is a coiled spring 100 on the rod between the two blocks. The block 99 is rigidly connected to an arm 101 which is rigidly attached to the upper rack bar 79, as indicated at 102.

The action of the barrier is substantially as follows: When the lower rack bar is pulled out, due to a purchaser pulling on the handle 46, the upper rack bar 79 is moved in the reverse direction, due to their toothed interconnection with the pinion 76. The inward movement of this upper rack bar through the medium of the arm 101 carries the forward block 99 and through the medium of the spring 100, the inner block 95 is then shifted. This latter block carries the barrier plate, which passes through the slot 25 in the magazine 13 being shifted from the position of Fig. 1 to that of Fig. 2.

Should the forked end 92 of the barrier plate engage an article to be vended such as an orange or apple whose lowermost point is not quite in line with the barrier, the spring 100 may become compressed to a sufficient extent to prevent injury to the fruit, but not sufficient to prevent insertion of the barrier between the lowermost fruit and the one next above; thus the barrier provides a device for supporting the column or stack of fruit in the magazine after the lowermost one has been vended by dropping through the trap door 17. The fruit, when vended, rolls down and is dispensed through the chute 104 (Fig. 3).

In the return action the weight of the fruit tends to hold the barrier plate 91 until the cotter pin 98 engages the inner block 95, thus holding the stack of fruit in the magazine until the trap door 15 is completely closed and caught by the catch 19 as above explained.

From the above description, together with the illustrations, it will be seen that I have developed a simple type of vending machine which is suitable for fruit or other irregular-shaped articles. These, as indicated, may be arranged in a suitable stack, one above the other. It is, however, to be understood that I may have a magazine with a plurality of stacks of fruit of different means, the magazine being shiftable as is common in vending machines so that any particular article may be vended.

Various changes may be made in the principles of my invention without departing from the spirit thereof, as set forth in the description, drawings and claims.

I claim:

1. A vending machine having a magazine, means to support a stack of articles, one

above the other, therein, a movable barrier in the form of a plate having a pair of prongs to engage a spherical article, an inner block connected to said plate, a rod 70 slidable through said block, an outer block connected to the rod, a spring between said rods, and means to reciprocate the outer block, said reciprocating motion thrusting a barrier between a lowermost article in the magazine and the article next above. 75

2. A vending machine having a magazine for a stack of articles one above the other, a trap door forming a support for the lowermost article, a catch securing said trap door in closed position, a movable structure having a trigger to release the catch to allow opening of the door in one direction of movement of the said structure, and a roller to directly engage and lift the door and close the door on another movement of the structure. 80

3. A fruit vending machine having a magazine for a stack of articles, one above the other, a trap door pivotally connected to the magazine and forming a bottom closure 90 to support the said articles, a pivotally mounted catch engaging the door and holding same closed, a spring retaining said catch in engagement with the door, a movable structure having a trigger to engage 95 the catch and compress the spring, thereby releasing the door on the movement of the said structure in one direction, an arm having a roller connected to the said structure, said roller engaging the door and closing 100 the door on the reverse movement of the said structure.

4. A vending machine comprising in combination a magazine for a stack of articles, a supporting device to retain the lowermost article in the magazine, a lower rack bar having means to open and close the supporting device for the stack of articles, a pinion meshing with the rack bar, a second rack bar, a barrier plate connected thereto, said barrier plate being insertable into the magazine and between the lowermost article and the one next above, and means to operate one of the rack bars. 105

5. A vending machine comprising in combination a magazine having a pivotally mounted trap door to support the lowermost of a stack of articles, a catch securing said door closed, a slidably mounted rack bar having a trigger to release the catch and an arm with a roller to close the door, a pinion meshing with the rack bar, a second slidably mounted rack bar meshing with the pinion, a slidable barrier plate connected to the second rack bar and shiftable to be interposed 115 between the lowermost article and the one next above, and means to operate one of said rack bars. 120

6. A vending machine comprising in combination a slidably mounted lower rack bar 125

having an operating rod with a handle, a magazine having a pivotally mounted trap door at its lower end to support the lowermost of a stack of articles, a catch pivotally mounted on the magazine and having a tooth engaging with the trap door, a spring normally pressing said catch into engagement with the door, a trigger connected to the rack bar to release the catch by compressing the spring in the outward movement of the rack bar, an arm connected to the rack bar having a roller to engage the trap door and close same on return motion of the rack bar, a pinion mounted on a fixed axis meshing with the rack bar, a second rack bar meshing with the pinion, a barrier plate off-set to one side from the second rack bar and shiftable partly across the magazine to support the stack of articles above the lowermost article after opening of the trap door.

7. A vending machine, as claimed in claim 6, the barrier plate having a pair of prongs at its outer end and having a mounting with a spring, said spring allowing a stopping movement of the barrier plate on engaging an article and allowing further movement of the second rack bar.

8. In a vending machine having a magazine, means to support a stack of articles one above the other therein, a movable barrier positioned below the magazine in the form of a plate having a pair of prongs to engage a spherical article, and means to insert said barrier between a lowermost article of the stack and the article next above.

9. In a vending machine having a magazine, means to support a stack of articles one above the other therein, a movable barrier in the form of a plate having a pair of prongs to engage a spherical article, means forming a resilient mounting for the barrier adapted to allow displacement thereof on the plate striking one of the articles, and means to shift the plate forming the barrier between the lowermost and the article next above in the stack.

10. In a vending machine having a magazine, means to retain a stack of articles one above the other in the said magazine, the said retaining means releasing the lowermost article, a barrier plate positioned to enter the magazine, means to shift the plate between the lowermost article and the article next above in the stack on the release of the lowermost article, means having a lost slip motion to withdraw the said barrier plate, and means operable by the weight of the article resting on the plate whereby the said plate is held temporarily underneath the stack of articles on the partial withdrawal of the lost slip motion means.

11. In a vending machine having a magazine, means to retain a stack of articles one above the other in the said magazine, the

said retaining means releasing the lowermost article, a structure having a guideway, a barrier plate slidably mounted therein and positioned to enter the magazine, means to shift the plate between the lowermost article and the article next above in the stack on release of the lowermost article, and means having a lost slip motion to withdraw the said barrier plate, the weight of the articles resting on the plate increasing the friction between the plate and the guideway whereby the plate is held temporarily underneath the stack of articles on the partial withdrawal of the lost slip motion means.

In testimony whereof I have signed my name to this specification.

NELS P. PETERSEN.
